REFLECTOR UNIT

Charles Hallam Mahoney and William Stanley Brian, Owensboro, Ky., assignors to Ken-Rad Tube & Lamp Corp., Owensboro, Ky., a corporation of Delaware

Application February 20, 1939, Serial No. 257,492

9 Claims. (Cl. 88—82)

This invention relates to reflecting units of the type generally known as reflector buttons which include a refractory lens and a mirror suitably assembled to be handled as a unit for reflecting light rays when mounted in signs or other supports.

One of the principal objections to devices of this type is that the metallic mirror or reflector soon becomes tarnished in use, and the efficiency of the unit is consequently impaired. The lens itself being made of glass, and usually mounted in a protective casing or shell remains unchanged and seldom becomes damaged, and, therefore, ordinarily lasts much longer than the reflector because it is not subject to deterioration by the action of the elements or by moisture or gases. However, on the contrary, the reflector at the inner end of the lens becomes gradually tarnished by oxidation from air, gases or moisture entering the unit, or from condensation. This is particularly true when a silver reflector is used. Metallic silver when polished is the best available reflector but in most cases due to its tendency to tarnish or corrode it has been largely replaced by other and cheaper metals such as polished chromium or polished aluminum which, however, are of much lower reflective efficiency.

A primary object of the invention is to seal the reflector in the shell or cup in a novel way to thereby prevent deterioration of the reflector surface. While it has been heretofore proposed to enclose the mirror or reflector in a shell, and, also, in some cases to use a seal, nevertheless, cement of one type or another has been used for a seal and, moreover, so far as is known, no attempt has been previously made to hermetically seal the mirror under pressure. Cement and other seals heretofore employed are not permanent because as the atmospheric temperature changes, the glass lens, the metal cup and the cement, each having different coefficients of expansion, change in their relative sizes, and, as a result at some temperature the seal is broken. In addition, the small amount of air sealed in with the mirror will also expand or contract with a change in temperature thereby tending to break the seal and set-up a breathing action which tends to draw in some contaminating gas or substance. Therefore, previous attempts to effect a seal are not sufficiently effective to perform the intended function.

Accordingly, the present invention has primarily in view a construction wherein the reflector is hermetically sealed, with a resilient

gasket at the time of manufacture of the unit, against atmospheric attack in such a way that no gases or moisture can reach the reflecting surface thereby maintaining the original high reflecting power of the polished surface and, consequently, materially increasing the life of the unit as a whole. In that connection, the invention contemplates the manufacture of a reflector button wherein the seal, such as sulphur free rubber is applied by precision machine methods which afford no opportunity for poor workmanship which would result in a poor seal depending upon the skill of a particular workman. Where seals of cement or the like have been previously used, the operator may apply the cement poorly so that openings are left in the seal or in some cases the operator may even fail to put in the cement at all, or sufficient cement, according to his judgment. Moreover, the application of cement or like sealing mediums by individual operators is a tedious and chance operation.

A further object of the invention is to provide a construction which readily lends itself to standard manufacturing practices thereby making it possible to economically produce a unit of this type, that is, of the type wherein the reflector is hermetically sealed at the time of assembly so that at no time after it leaves the factory is it necessary to disassemble any of the parts with the consequent danger of admitting moisture or gases which will affect the reflector.

A general object of the invention is, therefore, to provide a reflector unit which is so constructed when it is first made as to give longer life and higher efficiency in use and in which the original efficiency of the reflecting surface is maintained even where silver is employed.

With the above and other objects in view which will more readily appear as the nature of the invention is better understood, the same consists in the novel construction, combination and arrangement of parts hereinafter more fully described, illustrated and claimed.

A preferred and practical embodiment of the present invention is shown in the accompanying drawing in which:

Figure 1 is a vertical sectional view of one form of unit constructed in accordance with the present invention.

Figure 2 is a fragmentary sectional view illustrating a step in the making of the unit.

Figure 3 is a vertical sectional view of a unit embodying a modified form of construction.

Figure 4 is another vertical sectional view il-

lustrating a further modification of the invention.

Similar reference characters designate corresponding parts throughout the several figures of the drawing.

Referring to Figure 1, it will be observed that the unit includes in its organization an outer shell or cup designated generally as 1. This shell is preferably metal stamping and, therefore, impervious to moisture, gases and other elements which would tend to act adversely on a reflecting surface. The upper edge of the shell 1 is provided with a flange 2 which assists in mounting the unit in a suitable support such as the surface of a sign or the like. Within the shell 1 there is provided a pair of spacing rings 3 and 4 which in effect provide abutment means for limiting the inward movement of the lens. These rings are so arranged as to clamp between the adjacent edges thereof, the peripheral edge portion of a suitable polished reflector or mirror 5. The lower edge of the ring 3 rests on the bottom wall of the casing 1 and the upper edge of the ring 4 constitutes an abutment or stop for the lens 6.

The lens 6 is made of pressed or molded glass and its side wall is provided with an annular offset rib 1. The outer surface of the rib snugly fits the inner surface of the shell, and, as will be apparent from the drawing, this arrangement provides a space between the body of the lens and the inner surface of the shell, one side of said space being bounded by a shoulder formed by the rib. In other words, the construction is such that the annular rib on the collimating lens 6 cooperates with the shell to provide a cavity within the shell. This cavity is intended to receive a compressible sealing medium 8. This medium may be of any material suitable for the purpose, such, for example, as a rubber sealing ring which may be conveniently applied or fitted to the lens before it is placed in the shell.

After the lens and sealing material are fitted in the shell, a compression ring is placed in the cavity between the lens and the shell as shown in Figure 2. This compression ring, designated generally as 9, includes a compression flange or ring 10 and a sealing flange 11, and when placed in the position shown in Figure 2, may be placed in a suitable compressing and sealing die whereby the entire ring 9 is forced into the cavity and against the sealing medium until the flange 11 abuts with the flange 2 of the shell. The flange 11 may then be welded to the flange 2 to permanently compress the sealing material and also permanently lock the lens in the shell. As will be observed from Figure 2, the flange 2 of the shell may be provided with suitable raised portions formed by pressing or displacing the metal of the flange to form lugs which assist in welding the flanges 2 and 11 together.

Under ordinary circumstances the sealing material 8 is compressed under a pressure of approximately 1500 pounds to the square inch thereby hermetically sealing the chamber or space between the lower side of the lens and the metallic reflecting surface 5. It will thus be apparent that with a seal of this type the reflector 5 is effectively shielded from attack by atmospheric conditions, moisture or gases which would tend to tarnish or oxidize the reflecting surface thereby making it possible to use polished silver as the reflector, or, on the other hand,

adequately protecting the polished surface of any metal of which the reflector may be made.

Figure 3 of the drawing illustrates a construction wherein the outer shell 1a is intended to receive the spacing rings 3a and 4a having the reflector 5a clamped therebetween as previously described. The lens 6a is provided with a shoulder 1a to form a cavity between the body of the lens and the inner surface of the shell. The said shell, however, is formed differently at its upper edge than the upper edge of the shell 1 shown in Figure 1. That is to say, the upper edge 2a of the shell 1a, while having the flange portion thereof bent outwardly to form a shoulder for assisting in fitting the shell to a support, nevertheless, originally, said flange has the major portion thereof directed upwardly as shown by the dotted lines 2b in Figure 3. When the flange is in the condition shown by dotted lines it will be apparent that the shell 1a may receive the glass reflecting lens 6a having the sealing ring 8a fitted thereto and abutting with the shoulder provided by the annular rib 1a. After the lens is placed in the shell so that the lower edge of the rib rests against the upper edge of the upper spacing ring, a sealing ring 12 is placed against the otherwise exposed side of the sealing gasket 8a and then the portion 2b of the flange 2a is pressed or spun from the dotted-line position to the full-line position shown in Figure 3 thereby compressing the sealing gasket in final position. The effect of compressing the gasket 8a is to hermetically seal the chamber of the shell which houses the mirror or reflector 5a.

A further modification of the invention is shown in Figure 4 of the drawing from which it will be observed that the shell 1b having the spacing rings 3b and 4b therein, and clamping the reflector 5b therebetween, is provided at its upper edge with an out-turned flange 2c. The lens 6b is provided with an annular rib 7b which fits snugly within the inner surface of the shell 1b. In this instance the sealing gasket 8b is placed on the glass body of the lens so as to engage the shoulder of the rib 7b which is farthest from the mouth of the shell. In other words, the compressible sealing gasket 8b is confined in the cavity or space bounded on opposite sides by the lens and the shell, and, also, by a shoulder of the rib and the upper edge of the spacing ring 4b. The outer shoulder of the annular rib 7b of the lens is engaged by a compression and locking ring 13 which presses the entire lens inwardly of the shell and effects compression of the sealing ring by movement of the entire lens. When the ring 13 abuts with the flange 2c at the upper edge of the shell these parts are welded together thereby securely holding the lens in the shell and at the same time permanently maintaining the rubber sealing ring 8b under compression thereby to effectually seal the chamber, in which the reflector 5b is mounted, from atmospheric attack.

In all of the constructions described, the resilient gasket such as sulphur free rubber will maintain a gastight joint between the glass lens and the metal cup at any temperature regardless of the expansion or contraction of any of the parts. Pressure alone, without the resilient gasket, would not insure a perfect seal at all temperatures to which reflector buttons are exposed. In contrast to previous practice, the present unit is completely finished when it leaves the machine.

For example, where cements are employed, between the cup and the lens, as previously set forth, the time necessary to neatly center the lens in the cup and the extra labor necessary to remove the particles of cement from the exposed portions of the lens and cup, materially slow-up production and add to the cost. Moreover, where cements are employed, time is required for the cement to set. During this period the assembly must be carefully held in special trays which take up factory space, and in addition the loading and unloading of the trays consume more time and labor.

From the foregoing, it will be apparent that the present invention provides a construction wherein a metallic shell or cup houses a reflector supported between spacing rings which are locked against movement in one direction by the bottom wall of the cup. In every instance the glass collimating lens is provided with an annular rib whose outer periphery snugly fits against the inner surface of the shell. Such arrangement provides a cavity defined by the inner surface of the shell, the side wall of the lens, and one of the shoulders of the rib on the lens. This cavity receives the resilient compressible sealing material, and, on compression of said material either by movement of a compressor ring, or by the movement of the lens itself, the compressible sealing medium becomes permanently compressed, thus, hermetically sealing the reflector housing chamber of the shell from all weather conditions and gases which would have a tendency to impair the efficiency of the reflector surface. In all forms of the invention the compression of the sealing medium is effected under high pressure, at the time of manufacture, and the metallic and glass parts of the unit need never be taken apart from the time they are finished at the factory until they are installed at the point of use.

Without further description, it is believed that the features and advantages of the invention will be readily apparent to those skilled in the art, and it will, of course, be understood that changes in the form, proportion and minor details of construction may be resorted to, without departing from the spirit of the invention and scope of the appended claims.

We claim:

1. In a reflector unit, an outer shell closed at its back and having an open mouth, a reflector within the shell, a lens having an annular rib, an annular member fitted within the shell and spacing the reflector from the lens, a second annular member fitted within the shell and held between the reflector and the back of the shell, a resilient sealing medium within the shell and engaging one shoulder of the rib, and annular means rigidly held at the mouth of the shell for permanently maintaining said sealing medium compressed to hermetically seal the reflector against atmospheric attack and to hold the lens in the shell, said rib and sealing medium being held between the first mentioned annular member and the said annular means rigidly held at the mouth of the shell.

2. A reflector unit, comprising, in combination, a tubular shell formed with a closed end wall and an open mouth and of uniform interior diameter from said wall to the mouth, a reflector within the shell, a lens including a cylindrical body having an annular rib of a diameter to fit within the shell below the open mouth thereof, an annular member within the shell and spac-

ing the reflector from the lens, a second annular member fitted within the shell between the reflector and the closed end wall of the shell, said annular members cooperating to limit inward movement of the lens, an annular compressible sealing gasket between the inner surface of the shell and the cylindrical body of the lens and engaging one side of the annular rib of the lens, and annular means rigidly held at the mouth of the shell for compressing the rib of the lens and the gasket together thereby to seal the reflector against infiltration of gases or other destructive matter.

3. A reflector unit comprising, in combination, a lens having an annular rib presenting inner and outer shoulders, a shell for receiving the lens, a plurality of rigid spacing rings fitted within the shell for limiting the inward movement of the lens, a reflector having its peripheral edge held between said spacing rings; a compressible sealing gasket confined between the inner surface of the shell, the outer surface of the lens, and the outer shoulder of the rib on the lens; and means carried by the shell for maintaining said sealing gasket permanently compressed within the aforesaid confining parts thereby hermetically to seal the reflector in the shell from atmospheric attack.

4. A reflector unit comprising, in combination, a shell open at one end and closed at the other, a reflector in the shell, a lens having an annular rib, abutment means within the shell for limiting inward movement of the lens and holding the reflector spaced from the lens, a rubber sealing gasket surrounding the lens at the outer side of said rib, means initially movable within the shell in a direction toward said abutment means to compress said rubber gasket against said rib hermetically to seal the portion of the shell in which the reflector is mounted, and means for securing the last mentioned means to the shell.

5. A reflector unit comprising, in combination, a cup-like shell having a flange at the mouth thereof, a lens body having an annular rib fitted in the shell, spacing rings within the shell for limiting the inward movement of the lens, a reflector having its peripheral portion held between the adjacent inner edges of said spacing rings, a compressible sealing gasket confined in the cavity formed by the inner side of the shell, the outer side of the lens body and the shoulder formed at the outer side of the rib on the lens; and a sealing ring of angular cross-section having one flange thereof engaging and compressing said sealing gasket and the other flange secured to the flange of the shell.

6. A reflector unit, comprising, in combination, a cup-like shell having a flange at the mouth thereof, a lens body having an annular rib fitted in the shell, spacing rings within the shell for limiting the inward movement of the lens, a reflector having its peripheral portion held between the adjacent edges of said spacing rings; a compressible sealing gasket confined in the cavity formed by the inner side of the shell, the outer side of the lens body and the shoulder formed at the outer side of the rib on the lens; and a non-compressible sealing ring fitted in the space between the shell and the body of the lens, and said flange on the shell being bent inwardly to engage said ring to force the same against and compress the sealing gasket to hermetically seal the reflector against atmospheric attack and hold the lens in the shell.

7. A reflector unit comprising, in combination,

a cup-like shell having a flange at the mouth thereof, a lens including a cylindrical body having an annular rib presenting opposite shoulders and fitted within the shell, a plurality of spacing rings within the shell for limiting inward movement of the lens, a reflector having its peripheral edge portion held between adjacent edges of said spacing rings; a compressible sealing gasket located in the space defined by the inner surface of the shell, a portion of the outer surface of the cylindrical lens body, the inner shoulder of said annular rib and the outer edge of the outer spacing ring; and an annular element rigidly secured to the flange of the shell and engaging the shoulder of the lens rib opposite that engaging the sealing gasket.

8. A reflector unit including a metallic shell closed at its bottom and open at its mouth, a flange projecting outwardly from the mouth of the shell, a reflector within the shell, a lens having an annular rib presenting opposite shoulders and fitted within the shell through the open mouth thereof, abutment means in the shell for limiting inward movement of the lens and holding the reflector spaced relative to the lens, a compressible sealing medium within the shell and engaging one shoulder of the rib, and an annular ring-like member substantially co-extensive in width with respect to the rib and

the flange of the shell and welded to said flange to maintain said rib and sealing medium compressed relative to said abutment means thereby hermetically to seal the reflector against atmospheric attack.

9. A gas tight and moisture-proof reflector unit including a metallic shell closed at its bottom and open at its mouth, a reflector within the shell, a lens having an annular rib presenting opposite shoulders and fitted within the shell from the open mouth thereof, annular abutment means in the shell for supporting the reflector, a ring for spacing the inner end of the lens from the reflector, said ring having its inner edge engaging the peripheral edge of the reflector, said annular abutment means and ring limiting the inward movement of the lens, a compressible sealing medium within the shell between the inner shoulder of the rib and the outer edge of said ring, and annular means secured to the mouth of the shell and engaging the outer shoulder of the rib to maintain said sealing medium confined under pressure between the ring and the inner shoulder of the rib hermetically to seal the reflector against atmospheric attack.
